E. C. Thompson & Co.,
His ATTORNEYS.

UNITED STATES PATENT OFFICE

JOHN C. SHELLER, OF CHICAGO, ILLINOIS, ASSIGNOR OF ONE-HALF TO FRANK E. WHITE,
OF CHICAGO, ILLINOIS, AND ONE-HALF TO WALTER B. HINTZE, OF CHICAGO, ILLINOIS

FUSE PLUG

Application filed December 11, 1929. Serial No. 413,282.

This invention relates to fuse plugs.

The object of my invention is the construction of a simple and efficient plug which can be used "to plug in" for electric irons, sweepers, connections or extensions, etc.

Another object of my invention is the improvement of the construction of the positive and negative contact devices of a plug, whereby a very efficient and practical device is produced at a relatively low cost of construction.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

20 Figure 1 is a view in side elevation of the socket plug and indicator plug in an assembled position, with the locking or connecting sleeve shown in section.

Figure 2 is a longitudinal central sectional view of my socket plug, while

25 Figure 3 is a view in elevation looking at the inner end of the same.

Figure 4 is a perspective view of the negative contact device of my plug.

30 Figure 5 is a perspective view of the positive contact device of my plug.

Figure 6 is a view in elevation, looking at the inner end of the locking or connecting sleeve.

35 Figure 7 is a view in elevation looking at the inner end of the indicator plug, while

Figure 8 is a longitudinal central sectional view of the same.

Figure 9 is a plan view of the fuse.

40 Referring to the drawings by numerals, my socket plug comprises a body 1 formed of any suitable non-conducting material, such as porcelain, and carried by the body are the positive contact device 2 (Fig. 5) and the negative contact device 3 (Fig. 4).

The positive contact device 2 is substantially L-shape including the body 4 and the foot 5. Extending laterally and inwardly from body 4 is a dove-tail tenon 6; this dove-

50 tail tenon is arranged near the middle of the

body 4. The body 4 and the tenon 6 are molded into the body 1 during the manufacture of the same, with the outer face of the foot 5 lying in the same plane as the inner face of the body 1 (Fig. 2). The body 1 is provided with two blade or prong sockets 7 with the inner bevelled end of body 4 extending into one of these sockets. 55

The negative contact device 3 comprises an enlarged body 8 from which extends a prong 9. This prong 9 is similarly bevelled at its outer end to the bevelled structure of the outer end of body 4. Integral with and extending outwardly from body 8 is a dove-tail tenon 10; the prong 9 extends outwardly 60 from body 8 near its center (Fig. 4). The prong 9 extends into one of the sockets 7 similar to the body 4. The outer face of body 8 is provided with grooves 11 that constitute part of the screw thread grooves 12 (Fig. 1) 65 70 of the non-conducting body 1.

The prong sockets 7 are sufficiently large to allow the usual prongs of a connecting device of a sweeper or curling iron or the like to be inserted thereinto, in contact with the positive and negative contact devices of the plug. It is to be understood that the foot of the positive contact device permits the current from the source of supply to pass into the plug whereas the return current flows 75 through the negative device and is grounded, on the receptacle in which the plug is screwed. The large or "bulged" body 8 of the negative contact device 3 does not extend to the edge of the inner face of the body 1, 80 but terminates short thereof, as is clearly seen in Figure 2. The body 1 is provided with an annular flange 12, which is notched at 13, 13 for the purpose hereinafter specified. The beveling of the portions of the positive and negative contact devices that are positioned in the sockets 7 is done to allow free insertion into said sockets of the prongs of the indicator plug, hereinafter described or of any extension unit for a sweeper or curling iron 85 or the like.

My indicator plug (Figs. 7, 8 and 9) comprises a body 14 which has a compartment 15 in which moves the head 16 on the inner end of the indicator 17. The body 14 is provided 100

with an annular flange 18 that is notched at 19, 19 similar to notches 13 on flange 12. The inner face of body 14 is transversely grooved at 20 and in the groove 20 is placed the inner 5 end of prongs 21. Screws 22 are placed through portions of body 14 with their threaded ends threaded into prongs 21 (Fig. 8); the heads 23 of said screws 22 are seated in sockets which are filled with preferably 10 wax 24; by removing the wax 24 access to the head is easily obtained. A fuse 25 is placed upon the prongs 21 and when the fuse is "blown", the indicator 17 will be projected a considerable distance indicating that the 15 fuse has been destroyed. In the inner face or end of body 14 are also wire receiving grooves 26.

When the indicator plug is placed upon the socket plug, as shown in Figure 1 and the 20 locking or connecting sleeve 27 is placed in position, the inwardly extending lugs 28 will have passed through the registering notches 13 and 19 and as the operator will have slightly turned this sleeve to cause lugs 28 to engage 25 the flange 12, the parts will be securely fastened together against accidental displacement. By turning the sleeve so that the lugs 28 will register with the notches 13 and 19, the sleeve can be quickly removed, and 30 then the indicator plug and the socket plug may be separated.

While I have described the preferred embodiment of my invention and illustrated the same in the accompanying drawings, certain 35 minor changes or alterations may appear to one skilled in the art to which this invention relates during the extensive manufacture of the same, and I therefore, reserve the right to make such changes or alterations as shall fairly 40 fall within the scope of the appended claims.

What I claim is:

1. In a device of the class described, the combination of a body, a negative contact 45 device formed as an integral part of said body, said contact device comprising a bulged body, a prong extending outwardly from said body near its center, a laterally extending dove-tail tenon formed on said bulged 50 body at one side and grooves formed on the opposite side of said body, said first mentioned body provided with screw thread grooves and said grooves on the contact body registering therewith, and a positive contact 55 device formed in said body.

2. In a device of the class described, the combination of a body, a piston compartment in said body, said body provided on its inner face with transverse grooves, prongs seated 60 in said grooves, screws extending through portions of said body and into said prongs, said body provided with screw head sockets, said screws having their heads seated in said sockets, filling means normally closing said 65 screw head sockets, and an indicator pro-

vided with a head movably mounted in said piston compartment.

3. In a device of the class described, the combination of a body provided with a piston compartment, said body provided with a transverse groove and with wire-receiving sockets, prongs seated in said transverse groove, screws extending through part of said body and threaded into said prongs, a removable fuse on said prongs contiguous to 70 said piston compartment, and a movable indicator in said piston compartment normally against said fuse.

4. In a device of the class described, the combination of a socket plug and an indicator 80 plug having their inner ends in engagement, said plugs provided on their inner ends with registering flanges, one of said flanges provided with lug-receiving notches, a locking sleeve mounted on said flanges, and said locking sleeve provided with lugs adapted to pass through said notches and engage the outer 85 face of one of said flanges for locking the plugs together.

5. In a device of the class described, the combination of a body provided with an outwardly-extending annular flange, said flange provided with transverse notches, an indicator plug provided with an outwardly-extending annular flange registering with said 90 flange of the body, a locking sleeve mounted on said flange of the indicator plug and engaging the side of said flange of the body, and said locking sleeve provided with inwardly-extending lugs passed through said 95 transverse notches and engaging the outer face of said first-mentioned annular flange.

In testimony whereof I hereunto affix my signature.
